UNITED STATES PATENT OFFICE.

MORRIS S. WRIGHT, OF WORCESTER, MASSACHUSETTS, ASSIGNOR TO M. S. WRIGHT COMPANY, OF WORCESTER, MASSACHUSETTS, A CORPORATION OF MASSACHUSETTS.

APPARATUS FOR CLEANING CARPETS OR THE LIKE.

1,186,868.

Specification of Letters Patent. Patented June 13, 1916.

Application filed August 5, 1912. Serial No. 713,309.

To all whom it may concern:

Be it known that I, MORRIS S. WRIGHT, a citizen of the United States, residing at Worcester, in the county of Worcester and State of Massachusetts, have invented certain new and useful Improvements in Apparatus for Cleaning Carpets or the like, of which the following is a specification, reference being had therein to the accompanying drawing.

10 This invention relates to an apparatus for cleaning carpets or the like and more particularly to suction cleaning apparatus having associated with the nozzle thereof sweeping or brushing instrumentalities such as illustrated broadly in my copending application Serial No. 630,726, filed June 1, 1911.

15 The invention has to deal more particularly with suction cleaners of the portable type embodying a vacuum chamber, vacuum creating means therefor, a push handle, and a removable wall for the vacuum chamber, which said wall takes the form of an inlet nozzle. It is oftentimes necessary to employ a carpet sweeper as well as a vacuum cleaner, 20 for the thorough cleaning of the floor, since while the suction cleaner will take up the dust, the same will not at times pick up and remove threads, pins or the like, as will a brush of the ordinary sweeper.

25 30 More particularly the invention includes the provision of a vacuum cleaner having suction means, a suction chamber, a nozzle having an inlet opening communicating with the chamber, a brush in the nozzle, and a receiver having a dust filtering wall in the suction chamber, the brush being adapted to pick up threads and heavier articles such as pins, needles and the like and to mechanically throw the same into said receiver while 35 40 the lighter particles such as dust are drawn through the nozzle inlet receiver by the suction means.

In my co-pending application referred to, I have illustrated a removable nozzle member at the front end of the vacuum chamber, and means for detachably supporting the same in position, and one of the objects of the present invention is to provide a nozzle with brushing instrumentalities associated therewith, the nozzle being of a character whereby the same attaching means for securing a brushless nozzle, such as illustrated in the co-pending application, may be employed for supporting the nozzle illustrated 50 55 in the present application. This makes pos-

sible the interchange, at will, of the nozzle with the brush or the nozzle without the brush.

Further improvements and novel details in the construction and arrangement of the various parts will be more particularly brought out in the detailed description to follow, which, for a clear understanding of the invention should be considered in connection with the accompanying drawings 60 65 forming a part hereof, and wherein is disclosed, for the purpose of illustration, a convenient embodiment of the invention.

In the drawings: Figure 1 is a longitudinal section of the apparatus, Fig. 2 is a side 70 elevation enlarged of the forward end of the apparatus with the sweeper applied, Fig. 3 is a front elevation of the apparatus, with parts cut away, Fig. 4 is a detail view, enlarged, of parts of the nozzle removed.

75 With more particular reference to the drawings, wherein corresponding parts are referred to by like reference numerals, 1 is the base of the apparatus, 2 a removable cover, 3 a horizontally extending wall and 4 a vertically extending partition forming 80 with the bottom wall 1 the sides 1^a, and horizontal wall 3 a vacuum chamber 5. Positioned on the horizontally extending wall 3 is the vacuum creating means 6 preferably 85 operated through the medium of pitman rods 7 operatively connected with the traction wheel or wheels 8, in any desired manner as in my copending application above referred to. The horizontal wall 3 is provided with an outlet opening 3^a communicating with a valve controlled inlet opening 6^a in the bottom wall of the pump, and the said pump is provided with a valve controlled outlet opening 6^b in the movable wall 90 95 thereof. A suitable push handle 9 is connected to the apparatus for imparting movement to the same. A suitable dust receptacle is provided by a filtering bag 10 positioned in the vacuum chamber 5, the receptacle 10 having at its open mouth a suitable collar 11 upon which are mounted one or more spring arms 12 adapted to abut against a suitable abutment 13 on the inner wall of the vacuum chamber.

100 105 A removable front end wall is provided for the vacuum chamber the same being indicated by the numeral 14 and taking the form of a dust inlet nozzle. This nozzle is provided with a brush chamber and said 110

chamber communicates with an opening in the lower edge of the nozzle and with an opening in the rear wall of the nozzle which latter communicates with the interior of the dust receptacle. A dowel and socket connection 15 is provided between the nozzle and the collar 11 of the dust receptacle whereby to accurately position the nozzle, the said connection of course being readily releasable. The nozzle is preferably yieldably held in position through the medium of one or more spring arms 16 secured at their upper end at 16^a to the outer surface of the nozzle and free at their lower end, and said arms conveniently have a seat 17 intermediate their ends adapted for the reception of a swinging bail 18 the side arms of which are pivoted to the sides 1^a of the apparatus. A suitable packing 19 is preferably interposed between the nozzle and the end of the apparatus as shown. The sweeper member proper preferably takes the form of a rotary brush 20 mounted upon a suitable shaft 21 projecting at opposite ends through the openings 22 in the sides of the nozzle. These openings 22 are of a size to permit bodily movement of the shaft 21 relative thereto for adjusting purposes as will presently be described. Secured to each side 30 of the nozzle in any suitable manner as by removable screws 23 are elongated plates 24 the same projecting at one end rearwardly beyond the nozzle 14 whereby to overlie the sides 1^a of the apparatus and said plates 24 having openings 24^a to register with the openings 22 in the sides of the nozzle. Mounted upon each of the plates 24 is an auxiliary adjusting plate 26 the latter being pivotally mounted at its rear end as through 40 a pivot bolt 27 adjacent the rear end of the plate 24 and having a hook part 28 at its forward end adapted to overlie the stem of an adjustable securing bolt 29 threaded to the wall of the nozzle. The adjusting plates 26 are also provided with oppositely disposed flanges 30 preferably struck up at the top and bottom of the plate thereby forming a suitable guide way for journal bearing plates 31 having apertures 30^a through 50 which project the ends of the shaft 21. Mounted upon suitable shafts 32 at the rear ends of the supporting plates 24 are suitable traction wheels 33 adapted to engage the surface and forming supports for the forward end of the apparatus. Also secured adjacent the terminals of the shaft 21 are wheels 34 adapted to engage with the wheels 33 and to be driven by the latter. The engagement between the wheels 33 and 34 is 60 preferably a frictional engagement and the wheels 33 and 34 are preferably provided with yielding tread surfaces 33^a and 34^a respectively. Suitable springs 35 are provided one at each side of the nozzle the same being secured at one end to the rear end of

the journal plate 31 and at an opposite end to the pintle 27, the purpose of which springs is to normally draw the friction wheels 33 and 34 into operative engagement with one another.

The operation may be reviewed as follows: The removable wall in the form of a combined nozzle and sweeper, is adapted to take the place of the ordinary dust inlet nozzle at the front end of the vacuum chamber. The nozzle is positioned on said front end of the vacuum chamber by simply registering the dowel and socket parts and swinging the bail member 18 into position in its seat on the spring arms 16 on the front of the nozzle. The wheels 33 being so positioned by the supporting plates 24 that they engage the surface, rotary movement will be imparted thereto by pushing the apparatus back and forth through the medium of the handle 9. The springs 35 will exert rearward movement to the journal plates 31 in which is mounted the brush shaft 21 and in this way the wheels 34 at the ends of the shaft 21 will be brought into engagement and held in engagement with the wheels 33 to the end that the wheels 34 will be rotated to thereby impart rotary movement to the brush 20. The elongated slot 22 permits of the movement of the brush shaft due to the action of said springs. Also because of the fact that the slot 22 is of a size to permit of vertical adjustment of the shaft 21, it is possible to accurately position the brush 20 relative to the surface, thereby accommodating for wear, etc., and when such adjustment is desired it is only necessary to loosen the bolts 29 and swing the adjusting plates 26 about their pivot 27 thereby raising or lowering the shaft 21 as desired, and when properly adjusted the plates 24 are locked in position by the securing bolts 29 in a manner that is obvious. The dust laden air and particles taken up by the brush will be drawn into the receptacle 10 through the medium of the vacuum created by the pumps superimposed on said chamber, while the heavier materials such as pins will be picked up by the brush and mechanically thrown into the receptacle. In cleaning the apparatus the nozzle with the sweeper attachment is removed by releasing the bail 18, when the dust receptacle 10 may be taken out and relieved of its contents.

What I claim is:

1. In a vacuum cleaner, the combination of a dust box, having a substantially unobstructed open end, a closure wall for said open end, said closure wall being hollow and having a rear opening to communicate with the dust chamber, and a lower edge opening, a brush positioned within said wall and of a diameter to project above the lower edge of the rear opening of the closure wall; a traction driving wheel for the brush carried

by the closure wall, and means for detachably connecting the wall to the dust box and positioning said driving means in contact with the surface.

2. In an apparatus of the character described, the combination of a box like casing forming a vacuum chamber, vacuum creating means, and a vertically extending removable wall for the casing forming a dust inlet nozzle, a traction wheel supported from said removable wall and forming a support for the front end of the casing, a brush within the dust opening of said wall, an operative drive connection between the brush and traction wheel including an auxiliary wheel connected to the brush and yieldable means for maintaining said wheels in operative engagement.

3. In an apparatus of the character described, the combination of a casing having a vacuum chamber, a removable end wall for said casing open at its lower edge to constitute an inlet communicating with the vacuum chamber, a rotatable brush positioned in said end wall and projecting through the lower end thereof, said end wall with the brushing instrumentalities being detachable as a unit to permit of the discharge of the dust and the like through the end opening of the casing, and adjustable supports at the ends of said end wall for the brush.

4. In a vacuum cleaner, the combination of a casing having relatively fixed sides and a rear end wall, a roller for supporting the casing adjacent the rear end thereof, a removable vertically extending front wall, said front wall having a brush chamber adjacent the lower end thereof opening out through the bottom of the front wall and communicating through an opening in the rear side thereof with the vacuum chamber formed by the casing, and a rotary brush having journal bearings on the ends of said front wall and operating through the opening in the bottom of said front wall, the periphery of the brush being adjacent the lower edge of the vacuum chamber casing opening.

5. In a vacuum cleaner, the combination of a casing having relatively fixed sides and a rear end wall, a roller for supporting the casing adjacent the rear end thereof, a front wall, said front wall having a relatively enlarged chamber adjacent the lower end thereof opening out through the bottom of the front wall and communicating through an opening in the rear wall thereof with the vacuum chamber formed by the casing, a rotary brush, adjustably mounted plates on the ends of the front wall, and a shaft in the brush projecting through the ends of said front wall and supported on said plates.

6. In a vacuum cleaner, the combination of a casing, a roller for supporting the cas-

ing adjacent the rear end thereof, a front wall, said front wall having a relatively large chamber adjacent the lower end thereof opening out through the bottom of the front wall and communicating through an opening in the rear wall thereof with the vacuum chamber formed by the casing, a rotary brush in said chamber, vertically adjustable supporting plates positioned on the ends of the front wall, said plates each having an elongated opening, a shaft on the brush projecting through the ends of the front wall and into said openings, whereby the brush is susceptible of independent adjustment, and a drive wheel for the brush operatively connected with the brush shaft.

7. In a vacuum cleaner, the combination of a casing having a front wall being hollow and having an inlet opening at its lower end connecting with an enlarged chamber opening through the rear of the removable wall into the vacuum chamber formed by said casing, a rotary brush positioned in the enlarged chamber of the hollow front wall, a shaft for the brush projecting through openings in the ends of the front wall, and a supporting plate at each end of the front wall said plate being pivotally connected at one end and having an adjustable securing connection at its opposite end and carrying a bearing intermediate its ends for this shaft.

8. In a vacuum cleaner, the combination of a casing having a removable front wall, said front wall being hollow and having an inlet opening at its lower end connecting with an enlarged chamber opening through the rear of the removable wall into the vacuum chamber formed by said casing, a rotary brush positioned in the enlarged chamber of the hollow front wall, a shaft for the brush projecting through openings in the ends of the front wall, a supporting plate at each end of the front wall, said plate being pivotally connected at one end and having an adjustable securing connection at its opposite end and also having an opening intermediate its ends for said shaft, a suitably supported friction wheel to engage the surface, a coöperating friction wheel carried by the brush shaft, and spring held plates one at each side of the removable front wall, said spring held plates being slidably mounted relative to the pivotally supported plates and being connected with the shaft of the brush whereby to normally hold said traction wheels in engagement.

9. In a vacuum cleaner, the combination of a horizontally disposed elongated casing having a vacuum chamber open at the front end, vacuum creating means, a supporting wheel at the rear end of the casing, a front end wall for the vacuum chamber forming a dust inlet nozzle, a brush within said front wall adapted to engage the surface of the

floor at the dust inlet opening, rearward projections on the ends of the front wall overlying the sides of the casing, supporting wheels for the front end of the casing,
5 said wheels having bearings in said rearward projections and operatively connected with the brush for rotating the same, and means for detachably connecting the front

wall with said connected parts in place on the casing.

In testimony whereof I affix my signature in presence of two witnesses.

MORRIS S. WRIGHT.
